UNITED STATES PATENT OFFICE.

NICHOLAS J. COONEY, OF CHICAGO, ILLINOIS.

LUBRICATOR.

Application filed October 12, 1922. Serial No. 594,105.

To all whom it may concern:

Be it known that I, NICHOLAS J. COONEY, a citizen of the United States, residing at Chicago, in the county of Cook and State of Illinois, have invented certain new and useful Improvements in Lubricators, of which the following is a specification.

My invention relates to improvements in lubricators, and more particularly to a lubricator adapted for use with the reciprocating elements of an air pump, engine or the like.

The invention has among its objects the production of a device of the kind described which is simple, convenient, compact, durable, reliable, efficient and satisfactory wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts;

Fig. 1 is an elevation showing the manner of using the device;

Fig. 2 is a vertical section through the device;

Fig. 3 is a section taken substantially on the line 3—3 of Fig. 1;

Fig. 4 is a section taken on the line 4—4 of Fig. 1;

Fig. 5 is a section taken substantially on the line 5—5 of Fig. 2;

Fig. 6 is a side elevation of the parts shown in Fig. 5 with the locking key omitted;

Fig. 7 is a side elevation of the upper adjusting part;

Fig. 8 is a section taken substantially on the line 8—8 of Fig. 9;

Fig. 9 is a section taken substantially on the line 9—9 of Fig. 8; and

Fig. 10 is a perspective view of one of the locking keys.

In the drawings, wherein I have illustrated the preferred embodiment of my invention, 1 represents a piston rod or other reciprocating element intended to be lubricated or swabbed. 2 represents the upper

cylinder of an air pump or the like and 3 the lower cylinder, either or both of which have pistons (as shown) movable therein and carried by the rod 1 and the oppositely-directed ends of the portions 2 and 3 being externally threaded, as at 4. A gland 5 is adapted to snugly encircle the rod 1 and have its outer circumferential portion 60 slideable within each of the parts 2 and 3 respectively, as shown more clearly in Fig. 65 2. The heads of these glands 5 have an annular flange thereon, externally threaded, as at 6, said flange being of the same diameter as the threaded portion 4 of the parts 2 and 3.

A cup-shaped member 7 is adapted to cooperatively engage and encircle the threaded portion 4 of the part 3 and has a radial web 8 intermediate its ends and dividing said member into two chambered portions, the 70 upper chamber being larger in diameter than the lower chamber and adapted to form a well to receive suitable packing material 9, such as waste or the like, which will absorb and retain a quantity of lubricant and swab 80 the moving piston rod. The lower portion of the part 7 is internally threaded, as at 10, to engage the threaded portion 4 of the part 3, but these threads 10 are preferably cut away at the inner end of the part 7 adjacent the web 8, as at 11, as shown in Fig. 2, to enlarge the chamber at its bottom, so that the threads 6 of the part 5 will only engage the threads 10 until all of the threads 10 have been moved past the threads 6, 90 whereupon the part 5 may have a limited movement axially of the part 7. In this manner the likelihood of losing the part 5 is obviated and the ease of assembly is increased.

Arranged in an annular series about the periphery of the upper and lower parts of the member 7 are lugs or projections 13 and 12, 12' respectively, whereby a spanner wrench or other equivalent means may be 100 used for tightening or loosening the parts. The lugs 12' are similar to the lugs 12, except that the side edges thereof are inwardly beveled so as to form an outwardly divergent wedge-shaped lug for a purpose to be more 105 particularly described.

The tubular part 18, somewhat similar to the part 7, is adapted to be secured to the part 2, so as to hold the gland 5 in place, said part 18 being cut away at the lower 110

portion of its threaded part similar to the cutaway portion 11 of the part 7 and for the same purpose. An annular series of lugs 19 are arranged about the part 18.

- 5 In order to prevent relative rotation between the parts 7 and 18, I have provided one or more keys extending between and engaging said parts, each of said keys provided with a portion 14 engageable between 10 the adjacent lugs 19 of the part 18, as shown more clearly in Fig. 3, and having an offset portion 15 at the lower end of the portion 14 adapted to seat upon the annular upper edge of the part 7, as shown in Fig. 2. A 15 pair of prongs or legs extend from the outer edge of the part 15 in a plane parallel to the portion 14, providing a space 17 between the legs. The legs 16 are arranged on either side of the beveled lugs 12', as shown more 20 clearly in Figs. 8 and 9, so that when the keys are in position there can be no relative rotation between the parts 7 and 18. A screen or other suitable material 20 is arranged about the portions 14 of the keys in 25 order to prevent dust or other foreign matter from reaching the swab or absorbent material 9; as well as preventing the swab from being blown out or displaced.

Any suitable means may be provided for 30 supplying oil or other lubricant to the swab absorbent material 9, but I have found it preferable to provide an oil cup 21, secured to the portion 2 of the engine or pump by means of a bracket 22, or other suitable or 35 equivalent device, the outlet of the oil cup having a duct 23 leading therefrom and through the screen 20, so as to deliver lubricant to the absorbent material 9.

Having thus described my invention, it is 40 obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

50 1. A lubricator for a reciprocating element comprising a hollow member having a threaded portion surrounding said element, a tubular member within said member and slidably encircling said reciprocating element and provided with a threaded portion at one end engageable with said first-mentioned threaded portion, said hollow member constructed to permit a limited axial movement of said second-mentioned member when assembled, but preventing the accidental separation thereof.

2. A lubricator for a reciprocating element comprising a hollow cup-shaped member having an internally threaded portion surrounding said element, a tubular member

within said member and slidably encircling said reciprocating element and having an externally threaded flange at one end cooperating with said first-mentioned threaded portion, said hollow members so constructed to permit a limited axial movement of said second-mentioned member when assembled and preventing accidental separation of said members.

3. A lubricator for a reciprocating element, comprising a hollow cup-shaped member provided with a radial web intermediate its ends to form a pair of spaced chambers, one of said chambers threaded and surrounding said reciprocating element, a tubular member within said chamber to provide a packing for said reciprocating part and having an externally threaded flange at one end engageable with said first-mentioned threaded portion, the bottom of said chamber enlarged in diameter whereby said second-mentioned tubular member may have a limited axial movement relatively of said cup-shaped member when assembled but preventing accidental separation of said parts, and means for conducting lubricant to the other of said chambers.

4. In a rod swabbing device of the kind described and in combination, a cup-shaped member provided with an opening therethrough of a size to slidably fit the rod to be swabbed, an oil swab arranged in said cup, and a swab retaining member enclosing the swab but permitting circulation of air about the rod.

5. In a device of the kind described and in combination, a reciprocating element to be lubricated, axially spaced packing means adapted to receive said element, one of said packing means provided with an oil chamber therein communicating with said element, a plurality of circumferentially arranged locking means extending between said packing means for preventing relative movement therebetween, and a screen 110 secured about the exterior of said locking means.

6. In a device of the kind described and in combination, a reciprocating element, packing means spaced thereon and provided with lugs circumferentially spaced about their peripheries, and keys extending between said packing means to prevent relative rotation therebetween, each of said keys comprising a part engageable between adjacent lugs of one of said members and having its opposite end straddling one of the lugs of the other packing means.

7. In a device of the kind described and in combination, a reciprocating element, packing means spaced thereon and having lugs circumferentially spaced about their exteriors, keys extending between said packing means to prevent relative rotation therebetween, each of said keys comprising a part 130

engageable between adjacent lugs of one of said members and having its opposite end straddling one of the lugs of the other packing means, and a screen mounted on said keys to more securely hold them in place against radial movement and prevent dirt from reaching said reciprocating element.

In testimony whereof, I have hereunto signed my name in the presence of two subscribing witnesses.

NICHOLAS J. COONEY.
